UNITED STATES PATENT OFFICE.

FREDERICK W. CHEETHAM, OF HYDE, COUNTY OF CHESTER, ENGLAND.

FELT HAT.

SPECIFICATION forming part of Letters Patent No. 394,336, dated December 11, 1888.

Application filed April 4, 1888. Serial No. 269,604. (No model.) Patented in England February 9, 1887, No. 2,014; in Belgium August 8, 1887, No. 78,502; in Italy August 8, 1887, XXI, 22,128, and XLIV, 94; in France August 9, 1887, No. 185,246; in Canada August 24, 1887, No. 27,496; in Austria-Hungary September 14, 1887, No. 12,345 and No. 37,839; in New South Wales September 19, 1887, No. 196, and in Brazil November 12, 1887, No. 528.

To all whom it may concern:

Be it known that I, FREDERICK WILLIAM CHEETHAM, a subject of the Queen of Great Britain, and residing at Hyde, in the county 5 of Chester, England, have invented certain new and useful Improvements in Felt Hats, (for which I have received patents in the following countries, viz: Great Britain, No. 2,014, dated February 9, 1887; Austria-Hungary, 10 No. 12,345 and No. 37,839, dated September 14, 1887; Brazil, No. 528, dated November 12, 1887; Belgium, No. 78,502, dated August 8, 1887; Canada, No. 27,496, dated August 24, 1887; France, No. 185,246, dated August 9, 15 1887; Italy, Registro Generale, Vol. XXI, No. 22,128, dated August 8, 1887, Registro Attestati XLIV, No. 94; New South Wales, No. 196, dated September 19, 1887,) of which the following is a specification, reference being 20 had to the accompanying drawing, in which the figure represents one of my improved hats in section.

The object of my invention is to produce a durable hat of fine finish at a low cost; and 25 the invention consists in a felt hat formed of a completely-felted body having an exterior or superficial veneer or covering of fine fur or wool free from proofing or stiffening material.

30 In the drawing, A represents a completely-felted hat-body, and B is the superficial covering or veneer of finely-ground wool or fur blown on the completely-felted body and felted upon it just sufficiently to make it adhere firmly. This finely-ground wool is merely 35 superficial, and does not become mixed with the previously-completed body, as the drawing plainly shows.

It will be seen that I have produced a hat 40 having an exterior finish equal to the very finest hats, and yet the expense is not near so great, as the body is formed of much coarser material, which, however, is not visible when the hat is in use. Any one skilled in the art 45 could, however, readily distinguish my improved hat by reason of its coarser interior

and finer exterior free from proofing or stiffening material and free from any mixture of the coarser material of the body A.

Heretofore hats have been formed of two 50 separate bats felted together, the outer one being the finer; but the article produced was a hat having a mixed body, as the finer material could not be kept on the outer surface. A hat has also been produced by hardening— 55 that is, partially felting—a bat of coarse wool, then blowing an exterior covering of finer wool thereon, and then felting the two until the hat was completely felted, and then proofing or stiffening it; but the article produced was 60 a mixed hat-body, or one the finer material in which was thoroughly incorporated with the coarser, and which finer material was also filled with the proofing or stiffening material, as I have demonstrated by actual experiment. 65 The bodies of my stiff hats are stiffened or proofed as well as felted prior to the application of the veneer, and in some soft felt hats a small amount only of stiffening material is added to the completely-felted body 70 prior to the application of the finer veneer.

For ladies' and children's use I sometimes form the completely-felted hat-body of one color and the veneer of another color, the effect of which is very pretty. By applying 75 the finer superficial coating after the body is completely felted and proofed I produce an article which is soft to the touch, because the finer wool or fur has not become incorporated throughout the coarser body and stiffened 80 like the hats in which the finer fur or wool is applied before the felting and stiffening processes.

I do not claim the process in this application, as the same forms the subject-matter of 85 my application, Serial No. 233,210, filed March 31, A. D. 1887.

Having thus described my invention, what I claim as of my invention is—

1. As an improved article of manufacture, 90 a napless felt hat formed of a completely-felted body having an external superficial

coating or veneer of comminuted staple free from proofing or stiffening material, substantially as set forth.

2. As an improved article of manufacture, 5 a napless felt hat formed of a completely felted and proofed or stiffened body and a superficial exterior coating of finely-ground or comminuted staple free from proofing or stiffening material, substantially as set forth.

In testimony that I claim the foregoing as 10 my invention I have signed my name, in presence of two witnesses, this 21st day of February, 1888.

FRED. W. CHEETHAM.
